UNITED STATES PATENT OFFICE.

WILLIAM FRANKLIN PALMER, OF CHARLESTON, WEST VIRGINIA.

INSCRIPTION PLATE FOR TOMBSTONES OR THE LIKE.

Application filed March 19, 1924. Serial No. 700,261.

To all whom it may concern:

Be it known that I, WILLIAM FRANKLIN PALMER, a citizen of the United States of America, and resident of Charleston, in the county of Kanawha and State of West Virginia, have invented new and useful Improvements in Inscription Plates for Tombstones or the like, of which the following is a specification.

10 This invention relates to inscription plates and more particularly to inscription plates with means for fastening the plates to concrete tombstones or the like.

The object of this invention is to provide 15 fastening means of the above character which consists of a sleeve having fins in the outer surface imbedded in the concrete and a bolt passing through a hole in the inscription plate for screwing the said plate 20 in the sleeve.

Another object of the invention is to provide an inscription plate having flexible projections around the bolt holes, and a sleeve imbedded in the concrete and a bolt 25 to wedge the said projections into the said sleeve.

Another object of the invention is to provide a fastening means for inscription plates adapted to securely fasten an inscription 30 plate to a tombstone or the like which shall be positive in its operation and practically rigid in its construction, to reduce the number of parts to a minimum and to produce a fastening that is simple and effective in its 35 operation.

Other objects will appear as the disclosure progresses. The drawings are intended merely to indicate a possible embodiment of the invention. It is obvious that the actual 40 needs of manufacture may necessitate certain mechanical changes. It is, therefore, not intended to limit the invention to the embodiment shown, but rather to define such limits in the appended claims.

45 In general, the device consists of a sleeve having fins on the outer surface imbedded in the concrete, a threaded lug within the sleeve for the reception of a bolt, and a bolt passing through a hole in the inscription 50 plate to screw into the said threaded lug, all arranged to securely fasten an inscription plate to a tombstone or the like.

For a more detailed understanding of the invention, attention is now called to the drawings in which a preferred embodiment

is shown illustrated. In these drawings, like parts are designated by like reference characters in all of the views.

Figure 1 is a front elevation of a tombstone showing an inscription plate fastened thereto.

Figure 2 is a fragmentary sectional view of the tombstone showing the sleeve imbedded therein.

Figure 3 is the same view as Figure 2 with the sleeve in section.

Figure 4 is a cross-section of a modified form of the invention with the bolt about to be inserted.

Figure 5 is the same view as Figure 4 with the bolt inserted.

Figure 6 is a rear view of a portion of an inscription plate.

Figure 7 is a section on line 6-6 of Figure 6.

Referring now to the drawings in detail, numeral 1 is a concrete tombstone and 2 an inscription plate. Imbedded in the concrete is a sleeve 3 having a flange 4 at the rear and a series of fins 5 on the outside. Within 80 the sleeve 3 is a tapered boss 6 having threads on the inside for the reception of a bolt 7.

As will be seen in Figure 3, when the bolt 7 is screwed in place the inscription plate 85 will securely be held against the face of the concrete and the fins 5 in connection with the flange 4, will prevent the sleeve from working loose.

In Figure 4 is shown a modified form of 90 the invention. The plate 2 has tapered flexible projections 8 on the inner side which lock in with a tapering portion of the sleeve 3'. Around the bolt 7 is a sleeve 10 which when the bolt 7 is screwed into the tapered 95 portion 9 of the sleeve 3'. Thus it will be seen that the inscription plate is firmly held in place and any tendency for lateral movement will be prevented.

The structure and operation of the novel fastening means has now been fully set forth.

What I desire to secure by Letters Patent 105 is:

1. In a device of the class described in combination, a sleeve, a flange on one end of the sleeve, fins surrounding the said sleeve, a threaded boss within the said sleeve,

an inscription plate and a bolt to securely fasten said inscription plate against the surface of a tombstone.

2. In a device of the class described in combination, a sleeve, a series of fins surrounding the said sleeve, a flange at one end of the said sleeve, a tapered boss within the said sleeve, the said boss being threaded, an inscription plate, and a bolt to securely 10 keep the said plate in place.

3. In a device of the class described in combination, a sleeve, a tapering portion on the inside of the said sleeve, an inscription plate, projections on the inside of the said 15 inscription plate and means for locking the said projections against the said tapering portion of the said sleeve.

4. In a device of the class described in combination, a sleeve, a tapering portion on 20 the inside of the said sleeve, an inscription plate, tapered projections on the inside of the said inscription plate, a bolt, a sleeve on said bolt, and a threaded boss on the inside of the first mentioned said sleeve all 25 arranged to firmly secure an inscription plate to a tombstone, or the like.

5. In a device of the class described in combination, a sleeve, a flange on one end of the sleeve, a series of fins around the outer 30 surface of the said sleeve, a tapering portion on the inside of the said sleeve, projections on an inscription plate the said 35 projections being in segments, a bolt, and a sleeve on said bolt, all arranged to force the

said projections against the said tapering 35 portion on the inside of the said first mentioned sleeve for securely locking the said inscription plate in place.

6. In a device of the class described in combination, a sleeve, a series of fins surrounding the said sleeve, a flange at one end, an inscription plate at the outer end and a tapered boss within the said sleeve, the said 40 boss being internally threaded.

7. In a device of the class described in combination, a sleeve, a series of fins surrounding the said sleeve, a flange at one end of the said sleeve, an inscription plate at the outer end, a tapered portion in the interior of the said sleeve, and a tapered boss 50 within the said sleeve, the said boss being internally threaded.

8. In a device of the class described in combination, an inscription plate, a bolt hole, 55 projections on the said plate, the said projections bent inwardly and surrounding the said bolt hole, a sleeve and means to bend the said projections against the interior of the said sleeve.

9. In a device of the class described in combination, an inscription plate, bolt holes, 60 tapered projections integral with the said inscription plate and surrounding the said bolt holes, the said projections being in segments.

65 In testimony whereof I affix my signature.

WILLIAM FRANKLIN PALMER.
